UNITED STATES PATENT OFFICE

GUSTAF W. ENGSTROM, OF RIVERSIDE, ILLINOIS, ASSIGNOR TO INTERNATIONAL HARVESTER COMPANY, A CORPORATION OF NEW JERSEY

CONDENSER SYSTEM FOR RAIL CARS

Application filed April 6, 1928. Serial No. 267,952.

The invention relates to self-propelled, steam-driven railway cars adapted, primarily, to be used as independent units. In a car of this type it is highly desirable to 5 dense the steam exhausted from the engine by which the car is propelled and re-use it, thus avoiding the necessity of either carrying a large quantity of supply water or of stopping at frequent intervals for the replenishment of the supply. Using again the 10 water condensed from the steam exhausted by the engine is not only an advantage in that it obviates the necessity of carrying a large supply and stopping frequently to replenish it, but it also has the advantage of 15 avoiding the precipitation of the solids in the additional amount of water otherwise required that deposits on the heating surfaces of the steam generator, thus reducing its 20 evaporating efficiency. Some of these solids are carried into and deposited on the walls of the engine valves and cylinders, having a deleterious effect on the lubrication. Using this water over again permits its injection 25 into the steam generator at a high degree of temperature, thus adding efficiency in avoiding the expenditure of heat to raise it from a lower degree. This requires the use of effective condensers for the steam; and, as 30 water for condensing purposes is not available, and it is impracticable to carry a sufficient quantity for this purpose, it is desirable that the condensers be air-cooled.

It is the principal object of the present invention to provide a simple and effective condensing system for the exhaust steam of the driving engine of such a car which will be effectively air-cooled at a minimum expenditure of power; which will not occupy space 35 which would otherwise be available for other purposes; which will add but little to the weight of the car, relatively; and which will be of sufficient capacity to carry any burden which may be put upon it and at the same 40 time be so flexible or adjustable that it may be readily expanded or contracted in capacity as need therefor arises.

The improved condensing system comprises in effect two independent condensers 45 located at the respective opposite ends of the

car at the top thereof, so designed and mounted with respect to the body of the car as to be cooled in part by air currents provided by the motion of the car. The condensing system also comprises a heating coil 55 so connected to the system that the exhaust steam may be used to a greater or less extent as desired for maintaining the temperature of the car. Other features of the invention will appear from the detailed description 60 hereinafter contained, the annexed drawings constituting a part of this specification, and the claims.

In the drawing and the following specification, there has been described a preferred 65 embodiment of the invention. It is to be understood, however, that the specific disclosure is for the purpose of exemplification only and that the scope of the invention is defined in the appended claims. In the 70 drawings,

Figure 1 is a side elevation of a steam driven railroad car embodying the invention;

Figure 2 is an enlarged vertical, sectional 75 view taken on line 2-2 of Figure 3;

Figure 3 is a vertical section taken on line 3-3 of Figure 2;

Figure 4 is an enlarged top plan view of 80 the right hand end of the car of Figure 1;

Figure 5 is a vertical section taken on line 5-5 of Figure 4;

Figure 6 is a vertical section taken on line 85 6-6 of Figure 5; and

Figure 7 is a fragmental plan view of the right hand end of the condenser of Figure 5.

The invention is applied to a so-called day coach adapted to carry passengers and also having a compartment for baggage; however, it is to be understood that the invention is not limited to such a coach construction, but may be employed in a variety of cars, for example, freight cars, which are used for the hauling of freight only, or baggage cars, express cars, locomotive service, or the like. Referring to 90 the drawings, the numeral 1 designates the body of the car which is of the so-called double-end construction, thus being capable of traveling in both directions without turning of the car. The body is mounted on the ordinary 95

nary car trucks and the car, as a whole, is adapted to be propelled by two steam engines 2 and 3, which may be of any desired type and horse power. These engines are suspended beneath the body of the car and are connected to the axles of the car trucks through propeller shafts 4, the shafts 4 being provided with universal couplings 5 and 6 to accommodate truck movement and spring motion. The engines 2 and 3 are preferably of such construction that they may be operated at full speed in either direction. The car shown in Figure 1 may be provided with very simple controls (not shown), for example, the ordinary throttle valve, reverse lever, and brake valve used in connection with steam locomotives.

The steam for operating the engines 2 and 3 is generated and superheated in a boiler 7 (shown in dotted lines in Figure 1). This boiler may be of any desired construction, but I prefer to use a boiler which is of the so-called flash type adapted to generate and superheat the steam in a minimum time and deliver the same therefrom to the engines under high pressure. I also prefer, although it is not necessary, to use a boiler which is automatically controlled as far as possible, decreasing cost of operation and increasing efficiency, and adding to the safety of the passengers. The fuel employed for heating purposes may be of any desired kind, the feed of which is controlled by a motor and blower arrangement 8 (not shown in detail, but indicated in dotted lines in Figure 1).

The water supplied to the boiler 7 for the generation of steam may be taken from the hot well 9, being fed to the boiler automatically by a suitable feed water pump (not shown). The arrangement may be such that, when starting up, the feed well 9 is supplied with water to a desired height from a tank or other suitable source, the water being supplied from such source thereafter only as the system as a whole needs replenishment, since, as will be described hereinafter, the invention provides for the condensing of the steam exhausted from the engines 2 and 3 so that the water may be used over and over again. Or, if desired, the water may be supplied directly to the boiler 7 from a suitable source when starting up, such source of supply being cut off after enough water is supplied for the operation of the system, after which the feed water pump supplies the boiler with water from the hot well 9. In this latter arrangement the main source of water may be cut in automatically, or otherwise, to replenish the system as a whole when necessary.

Steam is supplied from the boiler to the engine 2 by a pipe 10 and to the engine 3 by a branch pipe 10^a. The engine 3 exhausts its steam into a pipe 11, the engine 2 exhausting into the same pipe through a branch connection 11^a. The pipe 11 leads to a main header

pipe 12 located at the top of the car and leading to the condenser units at both ends of the car, as shown in Figures 1 and 3. The header pipe 12 has valves 13 and 14 mounted thereon to permit of cutting out of the condenser units, at either or both ends of the car, as desired.

The central portion of the car roof may be of the usual curved form, but, at the ends, the roof is substantially flat and lower than the central portion, to provide pockets 15^a to receive the condensers. At the ends of the respective pockets the curve of the roof may be reproduced in arches forming tunnels 16, 17 for conducting air to the respective pockets. The sides of the cutout portions are walled up to a desired height by side walls 15, as shown in Figures 1 and 2. Each of these pockets thus has an end opening and a top opening. The ends of the tunnels are covered with fine mesh screens 18 and 19, respectively, to readily permit the passage of air therethrough while preventing the passage of stones, cinders, etc.

In each of the pockets 15^a there are mounted a plurality of similar condenser sections 20. These sections are arranged in pairs 20^a, 20^b, 20^c, 20^d, 20^e, 20^f, and 20^g (Figures 1 and 4), each section being connected at its upper, inner end to the common header pipe 12 by branch pipes 21 (Figure 4). The condensers of each pair, respectively, slope downwardly in opposite directions away from the common header pipe 12 to present an inverted V-shaped formation, as shown in Figure 2. The pairs of condenser sections, at each end, are arranged side by side in, and form a roof or enclosure for the pocket. There are preferably employed four pairs of condenser sections at each end. The header pipe 12 carries the inner ends of the condensers, as shown in Figure 2, and is supported by one or more brackets 22, and the outer, lower ends of the condensers are supported by suitable supports or brackets 23 suitably attached to the condenser sections 20 (as at 23^a, Figure 5) and walls 15. The angular position of the condenser sections provides for drainage of the product of condensation back to the hot well 9, as will be referred to more fully hereinafter.

Each condenser section is of the same construction and, hence, only one will be described.

As shown in Figures 5, 6 and 7, each section is formed of end headers 27, 28, between which extend the tubes 25. If desired, and as preferred, relatively short tubes 25 are provided and connected to an intermediate header 26 (see Figure 5). The intermediate header is formed of two sections bolted together at 26^a. The headers 28 of the respective sections are connected to the header pipe 12 by the branch pipe 21, to which reference has been made, and the opposite and lower ends

of the sections are connected to drain pipes 29 by branch pipes 29^a opening into headers 27. To provide for the cutting in or out of any desired number of the pairs of condensers, valves 31, 32 and 33 (see Figures 2 and 3) are located in the header pipe 12 between the adjacent pairs of condensers. As already stated, upon the closing of valve 14, all of the condensers at that end of the car may be cut out; and the closing of the valve 31 will cut out the condenser pairs 20^c, 20^e, and 20^h; and the closing of valve 33 will cut out only the condenser pair 20^h. Thus, any desired number of condensers at either or both ends of the car may be cut in or cut out to provide a greater or lesser heat radiation surface or condensing area. The drain pipes 29 connected to the outer, lower ends of the condenser sections are connected by pipes 29^a and 29^b (Figure 1) to the hot well 9 so that the condensate from the condensers is returned to the latter for re-use in the steam generator.

Assuming that the car is traveling in the direction shown by the arrow in Figure 1, it is obvious that the movement of the car creates a draft through the screen 19 and pocket 15^a at that end of the car which is in advance, the air passing through the screen, the tunnel, and up through and past the condensers, thereby cooling them.

In order to insure the required air circulation when the car is at rest and to boost the draft set up by the traveling car, there is mounted a plurality of fans 34 in the tunnels 16 and 17. The number of fans employed may be varied as well as their speed of rotation, to vary the forced draft conditions as desired. The fans 34 are driven by electric motors 34^a, the motor arrangement being such that the fans at the opposite ends revolve to force the air in the same direction. Thus, the fans 34 at the then front end of the car rotate in a direction to drive the air into the pocket 15^a and up through the condensers; while the fans at the then rear end operate to draw air down through the condensers at that end, through the pocket 15^a, and expel the same through the screen 18. Upon reversal of direction of movement of the car, suitable means (not shown) are provided for reversing the direction of rotation of the fans, thus providing for the same effective condensing operation regardless of the direction of movement of the car.

The bottoms of the pockets 15^a are provided with a plurality of wells 35 so located that rain water, from snow and the like, which may enter the pockets, will find its way thereto and be drained through the pipes 36.

The car is provided with heating coils 37, (see dotted lines, Figure 1), which may be supplied with exhaust steam from the header pipe 12 by means of pipes 38, shown in dotted lines. The coils 37 are connected to the hot well 9, as at 39 (Figure 1), so that the water

of condensation from said coils may be returned to the steam generator.

Air catchers in the form of shields 40 are provided, as shown in Figure 1, to catch and direct the air derived from the motion of the car into the condenser sections. When the car is moving in the direction indicated by the arrow in Figure 1, the front shields 40 are inactive, and the necessary air can be caught through the screen 19. But, with the car moving in the direction stated, the rear screen 18 will catch no air. Thus, the rear shields 40 are faced in a manner to catch the necessary air and deflect it downwardly through the rear condensers.

From the foregoing description, the operation will be apparent. The steam from the generator 7 is conveyed to the engine and, after performing its work therein, is distributed to the condensers at the respective ends of the car or to so many of the sections thereof as are open to the header pipe 12. When it is desired to heat the car, a suitable amount of the steam is diverted to the heating coil 37, as heretofore explained. The steam is condensed in the condensers, or in the condensers and heating coil, as the case may be, and the water of condensation returned to the hot well from which it is again pumped to the generator, as above explained. It being desirable, for obvious reasons, that the water be returned to the hot well at as high a temperature as possible, only so many condenser sections are open to the distributing header pipe 12 as are necessary, under the conditions prevailing, to effect substantially complete condensation of the steam. When and if the draft caused by the motion of the car is insufficient to produce the required condensation, and also when the car is at rest but condensation is required to be maintained, the draft fans are put into operation, and when the car is in motion, as previously explained, the fans are so rotated as to re-enforce the effect of the movement of the car. Thus the condensing system may be so controlled as to condense substantially all of the steam from the exhaust of the engine without reducing its temperature far below the boiling point, so that comparatively little heat is required to again bring it up to the boiling point. The heating of the car is, of course, effected without substantial expense. Any loss of water can be made up from a suitable supply tank carried by the car.

What is claimed is:

1. In a car of the class described, adapted to be driven in opposite directions, a steam engine for driving the car, a generator for supplying steam to the engine, condensers so arranged at the respective opposite ends of the car as to be cooled by the contact of outside air therewith due to the movement of the car, pipes connected to the exhaust of the engine and to the upper ends of said condens-

ers, and pipes connected to the lower ends of said condensers for returning condensed steam to the steam generator.

2. A car of the class described, having 5 pockets formed in the respective opposite ends of the roof thereof, air cooled condensers in said pockets, a steam engine for driving the car, a generator for supplying the engine with steam, exhaust pipes for connecting the engine with the condensers, and drain pipes connected to the lower ends of the condensers for returning condensed steam to the generator.

3. A car of the class described, having 15 pockets formed in the respective opposite ends of the roof thereof, said pockets being open at the top and at the respective ends of the car, air cooled condensers extending across the tops of the respective pockets and 20 forming air tunnels with the bottoms thereof a steam engine for driving the car, a generator for supplying said engine with steam, pipes connected to the exhaust of the engine and to said condensers, and return pipes connected to the lower portions of said condensers for returning condensed steam to the generator.

4. A car of the class described, having a 30 pocket formed in the end of the top thereof, air-cooled condensers arranged to form a gable roof for the pocket, the space enclosed by the condensers and the bottom of the pocket being open at the adjacent end of the car, a header communicating with the adjacent ends of the condenser at the angle of the gable, a steam engine for driving the car, a pipe connecting the exhaust of said steam engine with the header, a pair of headers connected respectively with the condensers on 35 opposite sides of the gable, a steam generator for supplying the engine with steam, and pipes connected to the last mentioned headers for returning condensed steam to the generator.

45 5. A car of the class described, having a pocket formed in the top thereof adjacent an end of the car, series of condenser sections arranged in the pocket, a header connected to the uppermost ends of the condenser sections, valves for cutting out one or more of the condenser sections, a header connected to the lower ends of the condenser sections, a steam engine for driving the car, a generator for supplying the engine with steam, a pipe 50 connection connecting the first mentioned header to the exhaust of the steam engine, and a pipe for returning condensate to the generator.

6. In a car of the class described, a steam 60 engine for driving the car, condensing sections mounted on the car, a steam generator supplying steam to the engine, a pipe connected to the exhaust of the engine, branches therefrom leading to the respective condenser sections, valves in said branches for cutting

off the respective sections, and pipes for collecting and returning the water of condensation from said condenser sections to said generator.

7. A car of the class described, having 70 pockets formed in the respective opposite ends of the roof thereof open to the draft of air caused by the movement of the car, air-cooled condensers in said pockets, a steam engine for driving the car, a generator for supplying the engine with steam, pipes connecting the engine with the condensers, drain pipes connected to the lower ends of the condensers for returning condensed steam to the generator, and fans for directing currents of air on the condensers.

8. A car of the class described, having 75 pockets formed in the respective opposite ends of the roof thereof, tunnels leading to the respective pockets from the ends of the car, air-cooled condensers extending across the tops of the respective pockets, fans for forcing air against said condensers, means for reversing the direction of rotation of the fans, a steam engine for driving the car, pipes connecting the exhaust of said engine with said condensers, a generator for supplying said engine with steam, and pipes connected to the lower portions of the condensers for returning water of condensation to the generator.

9. In a power system, a steam engine, means for condensing the steam exhausted by said engine and returning the products of condensation to the steam source, said condensing means comprising a draft tunnel with forced draft means located adjacent one end thereof, a plurality of condensers covering the other end of said tunnel, said condensers being arranged in opposed pairs in V-shaped formation, connected to a common exhaust steam conduit and each condenser comprising an inlet header, cooling sections, means for rendering certain of said condensers ineffective without interfering with the others, an outlet header, and a conduit for carrying the products of condensation from said outlet header to the steam generating means.

10. In a power system, a steam engine, means for condensing the steam exhausted by said engine and returning the products of condensation to the steam source, said means comprising a draft tunnel formed in the roof of the car and having a vertical opening through the roof of the car and another opening arranged longitudinally of the car body and extending through the end of the car so that a normal draft of air passes therethrough which is increased as the car moves along, force draft means located adjacent said longitudinal opening for increasing the natural draft therethrough, a plurality of condensers covering the vertical opening of said tunnel, said condensers being arranged in opposed pairs in V-shape forma- 110 115 120 125 130

- tion, each pair being connected to a common exhaust steam conduit and each condenser comprising an inlet header, a cooling section, an outlet header, means for rendering 5 certain of said condensers ineffective without interfering with the others, and a conduit for carrying the products of condensation from said outlet header to the steam generating source.
- 10 11. In a power system for cars, a steam engine, means for generating steam and supplying the same to said engine, and means for condensing the steam exhausted by said engine comprising a main exhaust steam conduit connected to condensers arranged in a natural draft pocket at each end of the car so that the forced draft at one end of the car will pass through said respective pocket and condensers in one direction and a forced 15 draft at the other end of the car will pass through that respective pocket and condensers in an opposite direction.
- 20 12. In a double ended rail car adapted to travel in either direction, a body having a roof, an air catching tunnel in each end of the roof, a steam generator in the body, a steam engine in the body, a set of condensers in each tunnel, and air catching shields for directing air through the sets of condensers.

In testimony whereof I affix my signature.
GUSTAF W. ENGSTROM.
